LEG FOR AN ARTICLE OF FURNITURE OR THE LIKE

Filed Sept. 14, 1949

UNITED STATES PATENT OFFICE

2,587,283

LEG FOR AN ARTICLE OF FURNITURE
OR THE LIKEEarl C. Booth, Columbus, Ind., assignor to Arvin
Industries, Inc., a corporation of Indiana

Application September 14, 1949, Serial No. 115,653

4 Claims. (Cl. 311—109)

1

Articles of furniture and similar structures, such as tables, ironing boards, etc., are frequently provided with pivotally mounted legs movable between extended and retracted positions; and it is common practice to provide for holding the legs in extended positions, braces or links pivotally connected to the legs. This invention relates to such structures and has for its object the provision of a leg which will be strong and rigid and which can readily be attached to links or braces employed in holding it and/or other legs in adjusted position. A further object of the invention is to produce a leg of the type described which can readily be made of metal tubing.

In carrying out the invention, the leg is formed of two similar tubular metal members secured together at the outer end of the leg. Adjacent such outer end, the tubular members are collapsed to form portions of double thickness which are desirably curved in cross section. The collapsed, arcuate leg-portions are arranged in opposed relation with their concave faces directed toward each other. In addition, the collapsed arcuate portions of the legs are offset transversely of themselves to permit their extreme outer ends to be secured together and in contact with each other, while the offset portions are spaced apart inwardly of such points of contact to provide for the reception between them of a brace or link pivotally connected to the leg by a pin or rivet extending through both of the collapsed leg-portions. In the preferred form of the invention, the two leg portions are formed of a single piece of tubing which, after being appropriately collapsed and given the desired form in cross-section, is bent about a transverse line to bring the two sections together.

The accompanying drawing illustrates the invention: Fig. 1 is a side elevation of a collapsible ironing board having a front leg in which my invention is embodied; Fig. 2 is a fragmental elevation illustrating a step in the formation of the preferred form of the front leg; Fig. 3 is a fragmental elevational view illustrating the outer end of the completed leg together with links and a brace connected to it; Fig. 4 is a vertical section on the line 4—4 of Fig. 3; and Figs. 5 and 6 are transverse sections on the lines 5—5 and 6—6 of Fig. 3.

The ironing board illustrated in Fig. 1 comprises a top 10 to which a front leg 11 and rear legs 12 are pivoted on spaced axes. The front leg 11 is connected to the rear legs 12 by links 13, so that the legs may swing jointly between collapsed positions against the lower face of the top

2

10 and the extended positions shown in Fig. 1. A releasable brace 14 serves to hold the legs in extended position. It is to be understood that the ironing board is illustrated merely as an example of a structure in which my invention may be employed, the invention in this instance being shown as embodied in the front leg 11.

As will be apparent from Fig. 3, the leg 11 is formed of two sections of metal tubing designated 11a and 11b, such two sections conveniently, although not necessarily, being different parts of a single length of tubing. If the two leg-sections are formed from a single piece of tubing, the intermediate portion of such tubing is formed as shown in Figs. 2 and 3 to include short flattened portions 16 separated by a crease 17 and extending to a point A spaced a short distance from such crease. As will be brought out more fully herein-after, the center portion of the single length of tubing is collapsed and otherwise shaped by a single stamping operation while such single length of tubing is straight; and thereafter the tubing is folded about the crease 17 to bring the two flattened portions 16 into contact with each other as shown in Fig. 3. Beyond the point A and continuing to the point B, each section of the tube remains collapsed but is given an arcuate or generally semicircular shape in cross-section to form a groove 18. Between the points A and B the edges of the leg-section are coplanar with the flattened portions 16, so that they will come substantially into engagement with each other, as indicated in Fig. 3, when the tubing is folded about the crease 17. Beyond the point B and continuing to the point C, the leg-sections are offset to provide between them the gap 19 shown in Fig. 3. In the leg illustrated, there is a second offset between the points C and D. The intermediate offsetting of the portions of the leg sections lying between the points B and C is provided for a purpose not material to the present invention and may be eliminated if desired.

Beginning at the point D, the groove 18 is of gradually diminishing depth, such groove disappearing entirely at the point E. In a leg where the two sections 11a and 11b diverge from each other as they continue upwardly, the bottom of the groove 18 between the points D and E in each section may be in alignment with the groove-bottom on the other side of the point D, the diminution in the depth of the groove being effected by bending the tube bodily at the point D. Beyond the point D, the two thicknesses of each leg-section, which have previously been in contact with each other, separate until, at and

beyond point E, the tube retains its original circular form.

When the tubing formed as above described is folded about the crease 17 to place the sections 11a and 11b in opposed relation, the offsetting of the arcuate shaped portions results in the gap 19 previously referred to and in the wider continuation 19' of such gap. As previously indicated, the fact that the gap shown has two different widths above and below the point C is not material to the present invention, it being sufficient for my present purpose only that the two sections of the leg be in contact with each other near the outer end of the leg and separated from each other above such point.

The finished leg is pivotally connected to the ironing board top 10 by coaxial pivot pins, bolts, or rivets 25 which pass through each leg-section. To interconnect the leg 11 with the links 13 and brace 14 a common pivot pin or rivet 26 extending through aligned holes in the leg-sections, braces, and links may be provided. The ends of the links and braces are desirably flattened, the link-ends are disposed against the outer surfaces of the leg sections, the brace-end is disposed in the gap 19', and the rivet 26 is put in place and headed to prevent its removal.

The finished leg may be provided with an appropriate foot 30. Conveniently such foot is made of resilient material such as soft rubber provided with a socket which, interiorly, conforms generally to the shape of the extreme lower end of the leg and has lateral pockets to receive the ends of the flattened portions 16. Such a socket would be resiliently distorted to permit it to be passed over the flattened portions 16, but will resume its original shape when in position, and the presence of the ends of the flattened portions in the pockets will locate and secure the foot and leg together.

I claim as my invention:

1. A leg for incorporation in an article of furniture or the like, said leg comprising a pair of similar sections disposed in opposed relations and rigidly interconnected at their lower ends, each of said sections being formed of metal tubing, the tubing of each section for a distance above its lower end being collapsed and formed into an arcuate cross-section, said leg-sections

being arranged with the concave faces of the collapsed portions of the leg-sections in opposed relation, said collapsed portions including upper and lower stretches, the latter having their edges in contact with each other and the former being spaced apart, and a transverse pin extending between said upper stretches to provide a pivotal support for a member received therebetween.

- 10 2. A leg for incorporation in an article of furniture or the like, comprising a single length of metal tubing having a collapsed center portion and circular end portions, said collapsed center portion being flattened at its midpoint and 15 of arcuate cross-section on both sides of its midpoint, said tubing being bent at said midpoint to bring the portions of arcuate cross-section into parallel relation with their concave faces in opposed relation.
- 20 3. A leg as set forth in claim 1 with the addition that said two leg sections are formed from a single length of tubing bent double at its midpoint.
4. The invention as set forth in claim 2 with 25 the addition that the width of said flattened center portion is materially greater than the maximum dimension of said portions of arcuate cross-section, and a foot formed of resilient material and having an upwardly opening, leg receiving 30 recess provided near its bottom with diametrically opposite pockets receiving the ends of said flattened portion.

EARL C. BOOTH.
